UNITED STATES PATENT OFFICE.

JOHN P. CLARY VON CARLSBERG, OF WORCESTER, MASSACHUSETTS.

PICTURE-HANGER.

1,273,426.

Specification of Letters Patent.

Patented July 23, 1918.

Application filed April 4, 1918. Serial No. 226,610.

To all whom it may concern:

Be it known that I, JOHN P. CLARY VON CARLSBERG, a citizen of the United States of America, residing at Worcester, in the 5 county of Worcester and State of Massachusetts, have invented certain new and useful Improvements in Picture-Hangers, of which the following is a specification.

My invention relates to improvements in 10 picture hangers of that type embodying a plate so secured to a picture frame as to render the frame capable of being hung upon a wall directly upon a nail or other fastening means or the picture frame may 15 be suspended from the nail or like fastening means by the use of a flexible element connected to the plate.

The primary object of this invention is 20 the provision of a hanger of the above character which will be simple in construction and cheap to manufacture and one which can be secured to any type of picture frame.

Another object of the invention is the provision of a hanger for picture frames 25 constructed of a single piece of material and so constructed as to render it possible to secure the hanger to any type of picture frame in such a manner as to permit the picture frame to be supported upon the wall directly 30 upon a nail or other fastener driven into the wall or suspended from this fastener by flexible means which has one end secured to the fastener and its free end removably associated with the hanger.

A further object of the invention is the 35 provision of a hanger of the above stated character, which is provided with means whereby the hanger may be removably secured upon any type of picture supporting 40 means now in general use.

With these general objects in view and others that will become apparent as the nature of the invention is better understood, the same consists in the novel construction, 45 combination and arrangement of parts hereinafter more fully described, illustrated in the accompanying drawing, and then claimed.

In the drawing forming a part of this application and in which like designating 50 characters refer to corresponding parts throughout the several views,

Figure 1 is a fragmentary rear elevation

of the picture frame and molding illustrating the application of my improved hanger thereto.

Fig. 2 is a fragmentary vertical sectional view of the same.

Fig. 3 is a fragmentary rear elevation of the hanger illustrating the manner in which a flexible member may be associated with the 60 frame and held against displacement by my improved hanger.

Fig. 4 is a fragmentary vertical sectional view of the same.

Fig. 5 illustrates another modified form 65 of hanging the picture with the use of flexible suspending means.

Referring to the drawings, the numeral 5 designates a fragmentary portion of a picture frame of any desired construction 70 and configuration and this picture frame is provided with a suitable molding 6 which molding is used for ornamentation purpose and to this molding my improved hanger 7 is adapted to be secured.

The molding is provided centrally in its 75 rear side with a socket 8 which has its upper edge merging into a recess 9 which is concentric to the interior diameter of the socket.

My improved hanger comprises a disk-shaped plate constructed of any suitable metal and is fastened in the recess 9 by the fastening means 10 such as rivets, nails or the like.

The body of the hanger plate 7 is provided with a semi-circular opening 11, the straight wall of which is provided with substantially key-hole slot 12 which is adapted to receive between its side walls and against its top wall the shank of a supporting fastener such as a nail or the like which is driven in the wall so that the picture frame may be readily hung thereon.

It will be readily understood from the foregoing description that a picture frame 95 constructed in accordance with my invention and provided with this particular type of hanger plate may be readily hung upon the wall by positioning the head of the supporting fastener which is driven into the wall 100 within the socket 8 of the molding through the semi-circular opening 11 and then permitting the shank of this supporting fastener to be moved into the opening 12

formed in this plate thereby holding the picture against shifting laterally in any direction when hung.

In the modified forms shown in Figs. 3 5 and 4 the molding 6 is provided through its upper side with an opening 13 which communicates with a socket 14 formed in the rear side of the molding. A flexible element 15 is looped intermediate its ends and 10 has its free ends knotted as at 17 thus when the looped end is passed up through the opening 13, the knot will engage the top wall of the socket 14 thus preventing its entire removal from its socket but leaving a 15 sufficient length of the flexible member beyond the molding so that the picture may be readily hung or suspended from the supporting fastener which is driven into the wall and upon the shank of which the loop 20 of the flexible member is adapted to be arranged.

In the preferred forms when the flexible member 15 is used, the knot 17 is positioned in the rear of the plate 7 and the side portions of the flexible member are urged upwardly into the opening 12, thus the flexible

member is connected to the plate and the picture may be readily hung upon any suitable fastening member driven into the wall.

What I claim is new is:—

1. A picture hanger of the class described comprising a disk plate provided with a semi-circular opening the straight wall of which is provided centrally with a vertical opening adapted to receive the shank of a 35 suitable supporting fastening member as for the purpose specified.

2. In combination, a picture frame having a socket formed centrally in the rear side of one portion thereof, the wall of the socket terminating into a concentric recess at the upper edge thereof, a disk-shaped hanger plate secured in said recess and being concentrically related to said socket, said plate being provided with a semi-circular opening, the straight wall of which is provided centrally with a vertical opening adapted to receive the shank of a picture supporting fastener which is driven into a wall whereby said picture may be readily hung thereon. 50

In testimony whereof I affix my signature.

JOHN P. CLARY VON CARLSBERG.

Copies of this patent may be obtained for five cents each, by addressing the "Commissioner of Patents, Washington, D. C."
